Inventor:
MARY STARMER

Stanley B. Brock
Att'y.

UNITED STATES PATENT OFFICE.

MARY STARMER, OF NEWPORT NEWS, VIRGINIA.

APPAREL BELT.

Application filed June 20, 1922, Serial No. 569,624. Renewed August 27, 1924.

To all whom it may concern:

Be it known that I, MARY STARMER, a citizen of the United States of America, residing at Newport News, in the county of 5 Warwick and State of Virginia, have invented certain new and useful Improvements in Apparel Belts, of which the following is a specification.

My present invention relates to apparel belts, and especially to the construction of 10 cloth or fabric belts for waistline garments, for both men's and women's wear.

The primary object of the invention is the provision of a belt of this type which is 15 comparatively inexpensive in cost of manufacture, and may be fashioned with facility and convenience. By the utilization of the subject matter of my invention, a strong, durable, and permanently formed belt is 20 provided which is attractive and neat in appearance and which will maintain its form and shape during long and continuous wear.

With the above ends in view the invention 25 consists in certain novel features of construction and combinations and arrangements of parts involving an inner lining or stiffening member, and the outer casing, as will be hereinafter more specifically set 30 forth and claimed.

In the accompanying drawings I have illustrated one complete example and several modifications of the physical embodiment 35 of my invention wherein the parts are combined and arranged according to the best mode I have thus far devised for the practical application of the principles of my invention.

Figure 1 is a perspective view of a waist- 40 belt embodying my invention.

Figure 2 is an enlarged and exaggerated, transverse sectional view showing the formation of the belt, in which an adhesive, as tailors' cement, is utilized for securing together the adjoining, lower edges of the belt.

Figure 3 is a similar view wherein the lower edges are secured together by stitches.

Figure 4 is an edge view showing the stitches as used in Figure 3.

Figure 5 is a view showing a portion of the strip of lining material before it is fashioned as a lining strip.

Figure 6 is a view showing the lining strip as prepared for enclosure within the belt casing.

Figure 7 is a detail, perspective view showing a guide and stiffening member at the free end of the belt.

Figure 8 is a perspective view of a modified form of guide and stiffening member. 60

In order that the relation of parts may readily be understood I have illustrated in Figure 1 a usual type of belt 1 having a suitable buckle 2, and the exterior or outer casing 3 of the belt may be of desired cloth 65 or fabric. When used for men's wear, the exterior casing 3 may be of the same goods or material as that of the trousers, and when used for women's wear the casing 3 may be of the same material as used in a 70 skirt or coat, if desired. It will be understood of course that other goods may be utilized for either men's or women's wear, and there may be contrast between the colors of the belt and that of the garment 75 with which the belt is worn.

In making up the belt I utilize a lining or interior reinforcement made from a suitable piece of coarse and comparatively stiff, but flexible, material as 4 in Figure 5, and this strip when cut to desired dimensions is folded to its final form for the lining as indicated at 5. The lining as an article of manufacture comprises an upper bend or fold 6, and the two folds of the lining are 85 stitched together on a median line as at 7, the row of stitches extending from end to end of the lining and fashioning the lining with two free edges 8 and 9, which become the bottom edges of the lining when it is 90 encased in its casing 3.

The casing 3 is also fashioned from a folded strip of goods or material, with an upper bend or fold 10 having depending edges 11 and 12. In making up the belt 95 the lining is placed within the folded casing and the two edges 11 and 12 of the casing, which are longer than the complementary edges 8 and 9 of the lining, are bent or folded under and within the edges of the lining. In the exaggerated showing of the invention in Figure 2, these folded edges of the lining and of the casing, where they contact, are secured together by an adhesive, as tailors' cement, as indicated at 13, thereby securing together the edges of the lining and casing and also the adjoining faces of the edges of the casing. After the adhesive has been applied, the belt is 100 pressed to closely cement the parts and to 105 110

compress the edges for the purpose of fash-
ioning the belt with a smooth appearance
and uniform thickness.

In Figures 3 and 4, the adhesive may or
5 may not be used, but stitches, as 14, are
utilized to secure together the adjoining
folded ends or edges of the casing in which
the free edges of the lining are enclosed.
Then the bottom edge of the belt is ironed
10 or otherwise pressed to proper width and
form.

For reinforcing or stiffening the free end
of the belt, and for guiding the belt through
the buckle 2, I utilize a longitudinally ex-
15 tending member 15, as in Figure 7. This
member is preferably made of a piece of
japanned wire or other non-rusting mate-
rial, with end eyes 16, and the wire is
stitched or otherwise secured by means of
20 its eyes 16 to the lining. The stiffening
wire may be located within the folds of
the lining, or stitched to one of its outer
sides as in Figure 7, and in either case is
of assistance in maintaining the free end
25 of the belt, as passed through the buckle,
in extended position. The stiffening wire
prevents curling of the belt end, and as-
sists in holding the belt-end in position for
ready insertion through the buckle.
30 The stiffener 17 in Figure 8 may be sub-
stituted for the wire stiffener 15 of Fig-
ure 7, but is used in the same manner. This
device 17 may be made up of a metal plate
35 with perforations near its ends for secu-
ring, as by stitches, to the lining for per-
forming its described functions.

From the above description taken in con-
nection with my drawings it will be ap-
parent that I have provided a ready-made
40 lining which may be sold as an article of
manufacture for incorporation in tailor
made belts, or the belt may be manufac-
tured complete including the lining as an
element. The use of the double-fold in-
45 volving the complementary edges of the
lining and casing, eliminates the necessity

for the customary basting or temporary
stitching of the parts, thus saving time and
work or labor in the manufacture of the
belts. The adhesive may be applied along
50 the edges of the lining and casing by a
brush, the parts then pressed inwardly with a
paddle, and the lower edge of the belt may
then be ironed for proper finish. The ad-
dition of the stitches 14, which are perma-
55 nent, not only insure greater security for
the double folds at the edge of the belt,
but these stitches are substitutes for the
usual basting stitches.

The belt thus constructed insures a strong,
60 durable, and well braced structure com-
mending it for both its utility and orna-
mental features, and is capable of being
made up into various forms to meet dif-
ferent requirements.

65

Having thus fully described my inven-
tion, what I claim as new and desire to
secure by Letters Patent is:—

1. The combination in a belt with an in-
ner lining and an outer casing each formed
70 with return bends, the free edges of the
casing turned under and within the free
edges of the lining, and means for securing
the adjoining edges of the casing together.

2. The combination in an apparel belt
75 with a lining formed with a return bend
and a casing therefor formed with a return
bend, the free edges of the casing turned un-
der and within the edges of the lining, an
adhesive cementing the adjoining faces of
80 both the lining and casing and of the casing,
and a row of stitches joining the lower edges
of the belt.

3. A belt comprising a lining formed
85 with a return bend and a row of stitches
joining the folds of the strip to provide a
pair of free edges, a casing formed with a
return bend, the edges of the casing turned
under and within the free edges of the lin-
ing, and means for securing the adjoining
90 edges of the casing.

MRS. MARY STARMER.
